UNITED STATES PATENT OFFICE

2,376,059

DIOLEFIN PRODUCTION

Jean P. Jones, Bartlesville, Okla., assignor to
Phillips Petroleum Company, a corporation of
Delaware

Application June 2, 1941, Serial No. 396,342

8 Claims. (Cl. 260—680)

This invention relates to the production of low boiling diolefin hydrocarbons from more saturated low boiling hydrocarbons heavier than methane. It relates more particularly to the production of diolefins such as butadiene, pentadiene, isoprene, cyclopentadiene and the like by treating hydrocarbons of 2 to 5 carbon atoms per molecule in a combination of catalytic dehydrogenation and pyrolysis steps.

An appreciable number of diolefins such as those just mentioned have been known to the art for a number of years. These have been produced in a number of ways which have included cracking of heavier oils, the inter-reaction of acetylene and ethylene to form butadiene, catalytic or thermal conversion of alcohols, both of the same number of carbon atoms per molecule as the desired diolefin and of a fewer number of carbon atoms per molecule, as well as the dehydrogenation of the corresponding olefins which in turn may have been produced by the dehydrogenation of the corresponding paraffins. Diolefins have also been reported as being present in the pyrolysis products of light hydrocarbons, including even methane. There are enormous quantities of such lighter hydrocarbons which are potentially available for the production of such diolefins, but apparently most of the commercial installations and processes to date have been one of the more involved types previously mentioned rather than the direct conversion of cheap and abundant light hydrocarbons to diolefins.

I have now found that I can successfully produce substantial yields of low boiling diolefins in a process in which unsaturated hydrocarbons of 2 and 3 carbon atoms per molecule are converted at elevated temperatures and low pressures in combination with catalytic dehydrogenation of normal butane, normal pentane or isopentane. In one modification of my process the unsaturated C₂ and C₃ hydrocarbons are derived from the effluent of the catalytic dehydrogenation, and parts of the effluent of both of these steps are separated in a common separation step to eliminate undesirable constituents and to produce a suitable charge stock for one or both of the conversion steps. The charge to my process may comprise predominantly or consist of a single hy-

drocarbon material such as normal pentane, normal butane, isopentane or cyclopentane, or in one modification it may comprise a mixture of hydrocarbons of up to 5 carbon atoms per molecule which may be derived from a natural gas, but which more preferably will be derived from the effluent of a cracking still, and thus will contain unsaturated hydrocarbons as well as saturated hydrocarbons. Methane may be present in the charge stock and in the material charged to either of the conversion steps, but will generally not enter extensively into the reactions which take place under the most desirable conditions, but will be present primarily as a diluent.

It is an object of my invention to convert low boiling hydrocarbons into low boiling diolefin hydrocarbons.

Another object of my invention is to produce diolefin hydrocarbons from more saturated hydrocarbons of the same number of carbon atoms per molecule.

A further object of my invention is to convert low boiling paraffin hydrocarbons into high yields of diolefin hydrocarbons by a novel combination of catalytic and noncatalytic conversion steps.

Still another object of my invention is to effect a simple and novel combination of conversion and separation steps whereby hydrocarbons of 2 to 5 carbon atoms per molecule are efficiently converted into olefin hydrocarbons with high yields.

Further objects and advantages of my invention will become apparent from the accompanying disclosure and discussion.

The features of my invention will now be disclosed and discussed in connection with the accompanying drawing which illustrates diagrammatically by way of a flow sheet a manner of practicing my invention, together with auxiliary steps which may be incorporated with various modifications, of which the discussion will also serve as an example of my invention.

Referring now to the drawing a paraffin hydrocarbon material of 4 or 5 carbon atoms per molecule, which may be essentially normal butane or one of the pentanes as discussed, enters the system through pipe 10 and is passed through valve 11 to dehydrogenation unit 12. The dehydrogenation in unit 12 is preferably carried out in the presence of a suitable dehydrogenation

catalyst, and the dehydrogenation unit itself is comprised of suitable heating units or furnaces, catalyst chambers and the like known to the art for effecting and maintaining catalytic dehydrogenation of low boiling hydrocarbons. While the dehydrogenation, which is carried out in unit 12, should not be primarily of any destructive type, I have found that in order to obtain an optimum conversion of the hydrocarbon material charged to this unit an appreciable amount of destructive dehydrogenation takes place forming hydrocarbons of 2 to 3 carbon atoms per molecule, which are substantially unsaturated, as well as some methane. This is true when the dehydrogenation is carried out in a single step and also when it is carried out in more than one step with a separation of hydrogen and other light products and with a concentration of olefins between dehydrogenation steps. Both such types of dehydrogenation are contemplated for dehydrogenation unit 12 as will be more fully described hereinafter.

The effluent of the dehydrogenation passes through pipe 13 and valve 14 to an absorber or fractionating unit 15. The absorber 15 is preferably operated at a substantial superatmospheric pressure, such as one of 600 to 800 or more pounds per square inch, and suitable compression equipment not shown should be inserted between the dehydrogenation unit 12 and the absorber 15, as will be readily appreciated by those skilled in the art. In a preferred modification of my invention, the absorber 15 may not be very large and should be equipped at the top with suitable cooling means 16 to provide a reflux condensate. The absorber should contain bubble trays or any suitable type of packing known to the art, and in many instances about 8 to 15 bubble trays will be sufficient. The absorber should be operated so that a substantial proportion of the C₂ and heavier hydrocarbons including essentially all of the C₄ and heavier hydrocarbons are separated as a liquid, and C₂ and C₃ hydrocarbons together with substantially all of the methane and hydrogen will be separated as a gas. In the modification shown, the cooling means 16 cools and condenses the heavier hydrocarbons which flow down the absorber to dissolve and remove all C₄ and heavier hydrocarbons, along with some C₂ and C₃ hydrocarbons.

The gaseous effluent of absorber 15 passes overhead through pipe 17 and may be removed from the system through pipe 20 controlled by valve 21. This material, however, is preferably passed through valve 22 in pipe 17 to a low point of absorber 23 wherein it is contacted with a suitable absorption liquid to effect a separation of C₂ and heavier hydrocarbons from methane and lighter material. The methane and lighter material is removed from a high point of absorber 23 through a pipe 24 and may be discharged from the system through valve 25. While the operation of absorber 23 will be discussed in connection with the use of a light absorption liquid, it will of course be understood that other known means of separation may be used, suitable modifications of equipment being readily supplied and substituted by one skilled in the art. When a light absorption oil is used, an absorption pressure of 600 to 800 pounds will generally be found expedient. The rich absorption oil is passed from the bottom of absorber 23 through pipe 26 and valve 27 and through a heater 28 to the top of a stripper 30. Stripper 30 is operated at a low superatmospheric pressure such as about 25 to 50 pounds per square

inch gauge and at an elevated temperature such as about 200° F. The material which has been absorbed in absorber 23 is vaporized and passed from the stripper 30 through a pipe 31 and may be passed through a valve 32 and a valve 33 to absorber 15 or a portion thereof may be passed through pipe 34 and valve 35 for subsequent treatment to be described. If desired, a part of this material may be removed from the system through pipe 36 controlled by valve 37. Also, if desired, any part or all may be passed to separating unit 62, to be described, through pipe 38 and valve 39, from pipe 34, to remove all light materials. To aid in the removal of this material from the absorption oil a portion of the methane and lighter gases may be passed to a low point of stripper 30 from pipe 24 through pipe 40 controlled by a valve 41. Lean absorption oil is passed from the bottom of stripper 30 to a pipe 42 controlled by a valve 43 to an accumulator 44 which is provided with a vent 45 controlled by a valve 46. From accumulator 44 the lean absorption oil may be returned to the absorber 23 through pipe 47 controlled by a valve 48. A portion of the absorption oil may be removed from the system for purification if desired through pipe 49 controlled by a valve 50. Fresh absorption oil may be added to pipe 47 through pipe 51 controlled by valve 52.

30 The heavier part of the effluent of the dehydrogenation, and containing substantially all of the C₄ and heavier hydrocarbon material together with substantial amounts of C₂ and C₃ hydrocarbons, is passed as a liquid from the bottom 35 of absorber 15 through a pipe 60 controlled by a valve 61 to a separating unit 62. Separating unit 62 will comprise various fractionators, stills, solvent extraction units or the like as will be found most suitable for treating a material 40 charged thereto and producing the various fractions desired. In general it will be necessary to separate a hydrocarbon fraction comprising essentially hydrocarbons having the same number of carbon atoms per molecule and the same carbon skeleton structure as that of the hydrocarbon material charged through pipe 10 for recycle to the dehydrogenation unit 12, through pipe 63 controlled by a valve 64. It will also be desirable to separate a fraction comprising the diolefin 45 corresponding to this hydrocarbon material which is recovered in any degree of purity which may be desired for subsequent use, and which is represented by the butadiene fraction which is recovered from separating unit 62 through a pipe 55 65 controlled by a valve 66. Other diolefin hydrocarbons which may be present in the dehydrogenation effluent, or which may be present in the effluent of the pyrolysis step to be discussed, may be recovered from separating unit 62 through 60 one or more outlets represented by pipe 67 controlled by a valve 68. Undesirable heavy material such as tar may be discharged from the system through pipe 70 controlled by a valve 71 while any light material such as methane or 65 hydrogen may be discharged from the system through a pipe 72 controlled by a valve 73.

A C₂-C₃ fraction which will contain a substantial proportion of unsaturated hydrocarbons, 70 which will be primarily ethylene, propylene and perhaps some acetylene, is removed from separating unit 62 through a pipe 74 controlled by a valve 75 and is converted at a high temperature of the order of 1300 to 1700° F. and at a low pressure to produce an optimum yield of low boiling diole-

fin hydrocarbons. This material may be joined by a similar material passing through pipe 34 and is passed through conversion coil 76 in a furnace 11 wherein the desired conversion takes place. This conversion is preferably carried out in the absence of catalysts, although in some instances it may be found desirable to use some of the more stable metal oxide gel catalysts or natural occurring minerals to promote the desired conversion. The effluent of this high temperature conversion is passed through a pipe 78 controlled by valve 79 to suitable separation means such as the absorber 80. The absorber 80 may be operated under conditions similar to those described for absorber 15 by the aid of a cooling coil 81 in the top part which provides sufficient cooling for condensation of C₃ and heavier hydrocarbons so that gaseous effluent from the top thereof is essentially free of C₄ and heavier hydrocarbons. Suitable cooling and compression equipment not shown may be inserted in pipe 78 so that the material undergoing separation in absorber 80 will be at an optimum separation pressure and temperature. A gaseous material comprising methane and hydrogen, together with some C₂ and C₃ hydrocarbons, passes from the top of absorber 80 through a pipe 82 and may be discharged in part or entirely through a valve 83. However, I prefer that a large part or all of this material be passed from pipe 82 through pipe 84 controlled by valve 85 to pipe 17 for treatment in absorber 23 along with a gaseous material effluent at the top of absorber 15.

A liquid hydrocarbon material containing substantial amounts of C₂ and C₃ hydrocarbons and substantially all of the C₄ and heavier hydrocarbons present in the effluent from the conversion zone 76 is passed from a low point of absorber 80 through pipe 90. This material may be discharged from the system through a pipe 91 controlled by a valve 92 for such subsequent separation and other treatment as may be found desirable. However, I prefer to pass a large part or all of this material to separating unit 62 in which provision has already been made for separating hydrocarbon mixtures of this kind. All of the material passing from absorber 80 through pipe 90 may be passed directly to separating unit 62 from pipe 90 through pipe 93 controlled by a valve 94. In some cases it may be found desirable to separate heavy aromatic hydrocarbons and tar from this stream prior to its introduction into separating unit 62. If such a modification is desirable, the material passing through pipe 90 may be passed through a valve 95 to a simple fractionating unit 96. The undesired heavy hydrocarbon material is removed through pipe 97 controlled by valve 98, and low boiling hydrocarbons comprising unreacted C₂ and C₃ hydrocarbons together with the desired diolefins are passed from the top of the fractionating unit 96 through a pipe 100 controlled by a valve 101 to pipe 93 and separating unit 62.

My process is sufficiently flexible that it may be operated successfully and with high yields on any one of several types of charge stock which may be available from refining and natural gasoline sources. As previously discussed, the material charged through pipe 10 may comprise essentially normal butane or one of the pentanes hereinbefore mentioned. When a hydrocarbon fraction comprising essentially such a paraffin hydrocarbon together with a corresponding olefin hydrocarbon is available, this material may also

be charged to the system through pipe 10. The C₂ to C₄ or C₅ fraction which may be separated from the effluent of any known cracking system for the conversion of heavy oils or from a unitary conversion of propane and/or butane or the like is also a desirable charge stock for my process. Such a charge is preferably introduced to separating unit 62 through a pipe 102 controlled by a valve 103. In separating unit 62 such a charge stock is separated into a C₂—C₃ fraction suitable for charging to the conversion unit 76 and into one or more C₄ or C₅ fractions, each comprising essentially a hydrocarbon material of a single number of carbon atoms per molecule and of a single carbon atom skeleton structure, which may be charged to a catalytic dehydrogenation unit 12 through pipe 63. If the material charged through pipe 102 contains hydrocarbons such that 2 separate catalytic dehydrogenation units are desirable for treating the hydrocarbons separated therefrom, such units may be made a part of my process although not shown in detail, as will be readily appreciated by one skilled in the art. In such a modification, the effluent of each such dehydrogenation unit may pass to a common absorber 15 or each may be treated in a separate absorbing unit with the liquid material effluent therefrom passing separately to separating unit 62.

As previously stated, a dehydrogenation carried out in unit 12 is preferably carried out in the presence of a suitable dehydrogenation catalyst. It has been found that solid granular catalysts consisting of or comprising chromium oxide, especially a dark, unglowed variety, is a highly desirable material for this purpose. Other dehydrogenation catalysts known to the art, especially bauxite impregnated with a minor amount of an alkali metal oxide such as barium oxide and the like, may be used. The dehydrogenation pressure should not be very high, that is generally it should not exceed 50 or 100 pounds per square inch gauge, and in most instances it should be only slightly above atmospheric. At times a subatmospheric pressure may be used, but although a low pressure favors the dehydrogenation reaction, subatmospheric pressures will generally not be used in plant operations. A low partial pressure of the hydrocarbon material present along with a total pressure above atmospheric may be realized by dehydrogenating the hydrocarbons in admixture with a gas such as nitrogen, steam or the like as is known to the art. Although the presence of free hydrogen tends to have an adverse mass action effect, a small amount of free hydrogen in the charge stock often appears to have a beneficial effect upon the catalyst, especially on the initial portions of the catalyst with which the charge stock comes into contact. Other modifications of dehydrogenation operation known to the art may also be used. With a given dehydrogenation pressure and catalyst activity, the dehydrogenation temperature and reaction time will be interdependent and will have in general an inverse relationship. The dehydrogenation temperature will be within the range known for catalytic dehydrogenation, but preferably will not be in the upper part of the range but will be between about 700 and 1150° F. Lower temperatures, even with long reaction times, will give uneconomically low yields, and higher temperatures, even with very short reaction times, will result in excessive formation of low boiling hydrocarbon products. I prefer to operate under constant conversion conditions

with gradually increasing temperatures as a particular body of catalyst becomes deactivated. With a fresh body of active catalyst, which will produce satisfactory dehydrogenation at a relatively low temperature, a flow rate adapted to give dehydrogenation not far short of equilibrium, may be used. If this flow rate is maintained as the temperature is increased, to provide for a relatively constant extent of conversion as the catalyst becomes less active, the reaction conditions will generally be such at the higher temperatures that excessive deleterious secondary or side reactions are not encountered. The catalytic dehydrogenation may be carried out in a single step as shown or may be carried out in two or more steps with separation of hydrogen between steps and if desired also a concentration of olefins produced by a previous dehydrogenation step. Such operation is to be considered included in the broad aspects of dehydrogenation unit 12 with suitable auxiliary separating equipment being included as will be obvious to one skilled in the art. A preliminary dehydrogenation may be conducted before the material is charged to my process in which case a hydrocarbon fraction separated from the effluent thereof can be charged through pipe 10.

When more than one dehydrogenation step is used it will generally be found desirable to pass the recycle material from separating unit 52 through pipe 63 to the inlet of the second dehydrogenation unit as would be the effect if the material charged through pipe 10 were separated from a preliminary dehydrogenation unit.

The conversion effected in the low pressure pyrolysis zone 16 is such as to produce from the unsaturated C₂—C₃ hydrocarbons charged through pipe 74 an optimum yield of low boiling diolefins of the nature of butadiene, pentadiene, cyclopentadiene and the like. As disclosed in the copending application of Frey, Serial No. 396,344, filed June 2, 1941, it has been found that such optimum conditions exist when the reaction is carried out in a temperature range suitable for the production of low boiling aromatic hydrocarbons and for a period of time such that only a minor portion of such aromatics is produced. More specifically the conversion should be at a low pressure similar to that discussed for dehydrogenation unit 12 at a temperature within a range of about 1300 to 1700° F. preferably between about 1375 and 1550° F. for a period of time such that the effluent contains not more than about 10% by weight and generally not less than about 3% by weight of C₄ and heavier hydrocarbons which are a result of synthesis reactions. A simple tube coil reactor may be used with the first portion of the tube coil employed to heat the charge rapidly to a reaction temperature with reaction taking place in a continuation of the tube coil. In some cases it may be found desirable to have the reaction carried out in an enlarged reaction chamber which should be quite large in cross section in comparison to the cross section of the tube coil in which the preheating is carried out. The absorption units 15 and 80 may be operated under more or less similar conditions and in order to obtain efficient separation without excessive amounts of refrigeration should be operated at substantial superatmospheric pressures as discussed. The absorption liquid is provided by condensation of the heavier portion of the material charged to any one of the absorbers with a sufficient amount of the C₂ and

C₃ material being condensed that substantially none of the C₄ material escapes in the vapor phase in the overhead product. This has been found to be a simple and inexpensive way to obtain the desired separation, but it will be appreciated by those skilled in the art that other means for separating the effluent of any of the conversion steps may be used. The absorbent employed in absorber 23 may be a light absorption oil which is used in the closed cycle as discussed. In some instances, it may be found desirable to use a highly volatile absorption liquid such as butane or pentane in which case it will generally be found necessary to recover vaporized absorbent from the gaseous material passing through pipe 24.

It will be appreciated that the drawing is diagrammatic and that the application of my invention on a commercial scale will require the use of numerous pieces of conventional equipment such as pumps, heaters, coolers, separators, accumulators and the like not shown in detail but which may be readily adapted for any particular installation by one skilled in the art. No pumps or compressors for the various streams have been shown but the general flow of each stream has been indicated and discussed as has been the preferred operating conditions for each part of the process and suitable equipment can be readily supplied as may be found necessary in any particular case. The general process operating conditions and material flows have been disclosed and discussed sufficiently to serve as efficient guides for such purposes. It will be obvious to those skilled in the art that various modifications of my invention may be practiced as being included in the spirit of the disclosure and in the scope of the claims.

As an example of my process, normal butenes separated from the effluent of a dehydrogenation of normal butane, are introduced to the process through pipe 10 and are passed in admixture with recycle butenes from pipe 63, and in admixture with an inert diluent to dehydrogenation in unit 12, which is conducted in the presence of a catalyst comprising bauxite impregnated with five per cent barium hydroxide. The inert diluent material comprises nitrogen and the amount of such material is adjusted so as to provide a partial pressure of butenes within the dehydrogenation unit of about 0.25 atmosphere under the conditions of the reaction. The reaction is conducted under a total pressure of about one atmosphere to provide a positive pressure through the apparatus, and a dehydrogenation temperature of about 1225° F. The mixture of butenes and nitrogen is passed through the dehydrogenation unit at an effective space velocity of about 995 volumes per volume of catalyst per hour. The effluent from the catalytic dehydrogenation unit 12 has a composition on a diluent-free basis, shown in column 5 of the table and is passed to separating means 15, which separates the effluent from unit 12 into a light fraction having a composition, on a diluent-free basis, as shown by column 6, and a high-boiling fraction as shown in column 8, with the aid of an absorption oil. This light fraction together with the low-boiling effluent from absorber-fractionator 80, to be discussed, is passed to absorber 23 for separation of hydrogen, methane, and nitrogen from hydrocarbons heavier than methane. Such heavier hydrocarbons comprising essentially C₂ and C₃ hydrocarbons are separated from absorbent used

in absorber 23 and are passed to conversion coil 76 through pipes 31 and 34.

generation to a first separation means, separating said effluent into a C₂ and lighter fraction essen-

The heavier fraction of the effluent from the catalytic dehydrogenation unit 12 is removed from the bottom of absorber-fractionator 15 and is passed to the separating unit 62.

An unsaturated C₂—C₃ mixture of hydrocarbons is passed to the thermal conversion coil 76 in furnace 77, and is introduced to the coil through pipes 34 and 74. This charge stock, has a composition as shown in column 1 of the table, and is composed of C₂ and C₃ hydrocarbons produced in unit 12 plus recycled C₂ and C₃ hydrocarbons from the effluent of coil 76. This charge is reacted at about atmospheric pressure and an average temperature of about 1470° F. for a reaction time of one second. The effluent from coil 76 has a composition as shown in column 2 and is passed to the absorber-fractionator 80. From absorber-fractionator 80 a low-boiling material is separated through conduit 82 with a composition as shown in column 3, and is passed to absorber 23, as mentioned.

A higher boiling hydrocarbon material having a composition as shown in column 4 is passed from a low point of absorber 80 through pipe 90 to separating unit 62. From separating unit 62, butadiene is removed through conduit 65 and butenes are removed through conduit 63. The butenes so removed are passed to the catalytic dehydrogenation unit 12, as previously mentioned.

From the material charged to separating unit 62 through both conduits 60 and 93 is separated a butadiene concentrate and a C₂—C₃ fraction. Approximately 13.6 per cent butadiene is obtained from the material charged through these two conduits. The C₂—C₃ fraction is passed through pipe 74 and valve 75, and is mixed with material passing through pipe 34 to form the total charge shown in column 1.

This example is not necessarily to be construed as limiting the invention disclosed herein.

I claim:

1. A process for the production of low boiling diolefin hydrocarbons from more saturated hydrocarbons of 4 to 5 carbon atoms per molecule, which comprises subjecting a hydrocarbon material comprising such hydrocarbons predominantly of a single carbon skeleton structure and a single number of carbon atoms per molecule to dehydrogenation conditions of temperature and pressure to form a corresponding diolefin together with minor amounts of lower-boiling unsaturated hydrocarbons, passing an effluent of said dehydro-

tially free of C₄ hydrocarbons and into a C₂ and heavier fraction essentially free of methane, passing said C₂ and lighter fraction to an absorption means, passing a lean absorption oil to said absorption means, maintaining in said absorption means absorption conditions such as to remove substantially all C₂ and heavier hydrocarbons from methane and lighter gases, removing absorbed material from the resulting rich absorption oil and passing at least a portion thereof to a thermal conversion step, passing said C₂ and heavier fraction from said first separation means to a second separation means, separating from said second separation means a C₂—C₃ hydrocarbon fraction and passing same to said thermal conversion step, treating said hydrocarbons passed to said thermal conversion step at an elevated conversion temperature and a low pressure to produce an optimum yield of low boiling diolefins, passing the effluent of said conversion to a third separation means, separating said effluent into a C₂ and lighter fraction essentially free of C₄ hydrocarbons and a C₂ and heavier fraction essentially free of methane, passing said C₂ and lighter fraction to the aforesaid absorption means, passing said C₂ and heavier fraction to said second separation means, and recovering from said second separation means low boiling diolefins produced by said dehydrogenation and by said conversion.

2. The process for the production of butadiene from C₄ hydrocarbons more saturated than butadiene comprising normal butane and normal butenes which comprises dehydrogenating said more saturated C₄ hydrocarbons to butadiene with the simultaneous formation of unsaturated C₂ and C₃ hydrocarbons; separating the effluent of said dehydrogenation into a lighter fraction comprising C₂ and C₃ hydrocarbons together with lighter gases and a heavier fraction comprising C₂, C₃ and C₄ hydrocarbons; separating C₂ and C₃ hydrocarbons from the lighter gases in said lighter fraction and subjecting said hydrocarbons to treatment at an elevated temperature at low pressure effecting conversion of at least a part of said C₂ to C₃ hydrocarbons to butadiene with the simultaneous formation of C₄ hydrocarbons more saturated than butadiene; separating the effluent of said high temperature conversion into a lighter fraction comprising C₂ and C₃ hydrocarbons together with lighter gases and a heavier fraction comprising C₂, C₃ and C₄ hydrocarbons; admixing the last said lighter fraction with the

first said lighter fraction prior to the subsequent separation of lighter gases; admixing the heavier fraction from the dehydrogenation effluent with the heavier fraction from the effluent of said high temperature conversion; separating butadiene from the resulting mixture as product; separating C_2 and C_3 hydrocarbons from said mixture and passing said hydrocarbons to said high temperature conversion; and separating C_4 hydrocarbons more saturated than butadiene from said mixture and passing said hydrocarbons to said dehydrogenation step.

3. The process for the production of pentadiene from C_5 hydrocarbons more saturated than pentadiene comprising normal pentane and normal pentenes which comprises dehydrogenating said more saturated C_5 hydrocarbons to pentadiene with the simultaneous formation of unsaturated C_2 and C_3 hydrocarbons; separating the effluent of said dehydrogenation into a lighter fraction comprising C_2 and C_3 hydrocarbons together with lighter gas and a heavier fraction comprising C_2 to C_5 hydrocarbons; separating C_2 and C_3 hydrocarbons from the lighter gases in said lighter fraction and subjecting said hydrocarbons to treatment at an elevated temperature at low pressure effecting conversion of at least a part of said C_2 to C_3 hydrocarbons to pentadiene with the simultaneous formation of C_5 hydrocarbons more saturated than pentadiene; separating the effluent of said high temperature conversion into a lighter fraction comprising C_2 and C_3 hydrocarbons together with lighter gases and a heavier fraction comprising C_2 to C_5 hydrocarbons; admixing the last said lighter fraction with the first said lighter fraction prior to the subsequent separation of lighter gases; admixing the heavier fraction from the dehydrogenation effluent with the heavier fraction from the effluent of said high temperature conversion; separating pentadiene from the resulting mixture as product; separating C_2 and C_3 hydrocarbons from said mixture and passing said hydrocarbons to said high temperature conversion; and separating C_5 hydrocarbons more saturated than pentadiene from said mixture and passing said hydrocarbons to said dehydrogenation step.

4. The process for the production of isoprene from iso- C_5 hydrocarbons more saturated than isoprene comprising isopentane and isopentenes which comprises dehydrogenating said more saturated iso- C_5 hydrocarbons to isoprene with the simultaneous formation of unsaturated C_2 and C_3 hydrocarbons; separating the effluent of said dehydrogenation into a lighter fraction comprising C_2 and C_3 hydrocarbons together with lighter gases and a heavier fraction comprising C_2 to C_5 hydrocarbons; separating C_2 and C_3 hydrocarbons from the lighter gases in said lighter fraction and subjecting said hydrocarbons to treatment at an elevated temperature at low pressure effecting conversion of at least a part of said C_2 to C_3 hydrocarbons to isoprene with the simultaneous formation of iso- C_5 hydrocarbons more saturated than isoprene; separating the effluent of said high temperature conversion into a lighter fraction comprising C_2 and C_3 hydrocarbons together with lighter gases and a heavier fraction comprising C_2 to C_5 hydrocarbons; admixing the last said lighter fraction with the first said lighter fraction prior to the subsequent separation of lighter gases; admixing the heavier fraction from the dehydrogenation effluent with the heavier fraction from the effluent of said high temperature con-

version; separating isoprene from the resulting mixture as product; separating C_2 and C_3 hydrocarbons from said mixture and passing said hydrocarbons to said high temperature conversion; and separating iso- C_5 hydrocarbons more saturated than isoprene from said mixture and passing said hydrocarbons to said dehydrogenation step.

5. A process for the conversion of normal butane to butadiene, which comprises subjecting normal butane to a catalytic dehydrogenation to form butadiene, smaller amounts of C_2 and C_3 unsaturated hydrocarbons being simultaneously formed by side reactions, passing effluents of said dehydrogenation to a first separating means and separating said effluent therein into a lighter fraction comprising C_2 and C_3 hydrocarbons and essentially free of C_4 and heavier hydrocarbons, and into a heavier fraction comprising essentially C_2 to C_4 hydrocarbons and free of methane and lighter constituents, passing said lighter fraction to an absorption means and absorbing C_2 and C_3 hydrocarbons from the bulk of the methane and lighter constituents, recovering a C_2 — C_3 hydrocarbon fraction so absorbed, comprising also a minor amount of methane and lighter constituents, and returning a portion thereof to said first separating means, passing a further portion of said C_2 — C_3 hydrocarbon fraction to a high-temperature conversion step as hereinafter recited, passing said heavier fraction to a second separating means, recovering from said second separating means a C_2 — C_3 hydrocarbon fraction essentially free of methane and lighter and of C_4 and heavier constituents, admixing the last said C_2 — C_3 fraction with the aforesaid C_2 — C_3 portion and subjecting the resulting mixture to a high-temperature conversion at a low pressure under conversion conditions such as to form an optimum yield of butadiene, small amounts of more saturated normal C_4 hydrocarbons being simultaneously formed by side reactions, passing effluents of said high-temperature conversion to a third separating means and therein separating said effluent into a lighter fraction comprising C_2 and C_3 hydrocarbons and free of C_4 and heavier hydrocarbons and into a heavier fraction comprising essentially C_2 to C_4 hydrocarbons and free of methane and lighter constituents, passing the last said lighter fraction to the aforesaid absorption means, passing the last said heavier fraction to the aforesaid second separating means, recovering from said second separating means a normal C_4 fraction comprising unreacted normal butane from said dehydrogenation and normal butane produced as a by-product of said high-temperature conversion and passing same to said dehydrogenation, and recovering also from said second separating means as a product of the process a butadiene fraction comprising butadiene produced by dehydrogenation of normal butane and butadiene produced by conversion of C_2 — C_3 hydrocarbons.

6. The process of claim 1 in which a portion of the absorbed material removed from said rich absorption oil is passed to said first separation means, and recovering also from said second separating means a hydrocarbon material corresponding to said material charged to said dehydrogenation and containing hydrocarbons

7. The process of claim 1 in which a portion of the absorbed material removed from said rich absorption oil is passed to said first separation means, and recovering also from said second separating means a hydrocarbon material corresponding to said material charged to said dehydrogenation and containing hydrocarbons

effluent from said dehydrogenation and from said thermal conversion step, and passing same to said dehydrogenation.

8. A process for the production of low-boiling diolefin hydrocarbons from more saturated hydrocarbons of 4 to 5 carbon atoms per molecule, which comprises subjecting a hydrocarbon material comprising such hydrocarbons predominantly of a single carbon skeleton structure and a single number of carbon atoms per molecule to dehydrogenation conditions of temperature and pressure to form a corresponding diolefin together with minor amounts of lower-boiling unsaturated hydrocarbons, passing an effluent of said dehydrogenation to a first separation means, separating said effluent into a C₂ and lighter fraction essentially free of C₄ hydrocarbons and into a C₂ and heavier fraction essentially free of methane, passing said C₂ and lighter fraction to a second separation means and separating same into a C₂—C₃ hydrocarbon fraction and into a fraction containing methane and lighter gases, passing at least a portion of said

C₂—C₃ hydrocarbon fraction to a thermal conversion step, passing said C₂ and heavier fraction from said first separation means to a third separation means, separating from said third separation means a C₂—C₃ hydrocarbon fraction and passing same to said thermal conversion step, treating said hydrocarbons passed to said thermal conversion step at an elevated conversion temperature and a low pressure to produce an optimum yield of low-boiling diolefins, passing the effluent of said conversion to a fourth separation means, separating said effluent into a C₂ and lighter fraction essentially free of C₄ hydrocarbons and a C₂ and heavier fraction essentially free of methane, passing said C₂ and lighter fraction to the aforesaid second separation means, passing said C₂ and heavier fraction to said third separation means, and recovering from said third separation means low-boiling diolefins produced by said dehydrogenation and by said conversion.
